UNITED STATES PATENT OFFICE.

LUKE W. PARKER, OF MOUNTAIN VIEW, MISSOURI, ASSIGNOR OF ONE-HALF TO M. L. LANDRUM, OF MOUNTAIN VIEW, MISSOURI.

CHECK-PROTECTOR.

1,310,370.

Specification of Letters Patent.

Patented July 15, 1919.

Application filed February 13, 1918. Serial No. 216,895.

To all whom it may concern:

Be it known that I, LUKE W. PARKER, a citizen of the United States, residing at Mountain View, in the county of Howell and State of Missouri, have invented new and useful Improvements in Check-Protectors, of which the following is a specification.

The principal object of the invention is to provide a device on which a check is placed when being filled out so that the check may be permanently marked during the filling out operation, thereby preventing its being changed thereafter without leaving evidences of such an attempted change in the check.

Another object of the invention is to provide a device of this character which is simple in construction, durable and effective in operation, and which can be manufactured at low cost.

Other and further objects will appear as the invention is set forth in detail in the description which follows.

To the exact construction in which it is shown and described, the device is not to be restricted. The actual practical application may make manifest certain desirable changes or alterations and the right is claimed to make any which do not depart from the spirit of the subjoined claim.

In the accompanying drawings:

Figure 1 is a perspective view of the invention.

Fig. 2 is a section on the line 2—2 of Fig. 1.

Fig. 3 is a perspective view showing the manner in which the device is employed.

Referring to the drawings, there is shown a plate 1 made preferably of steel and rectangular in plan, the plate being made identical in size with the size of the check with which it is to be used. On the upper face of the plate it is provided with serrations 2, which extend diagonally across the plate, and these serrations are crossed with further serrations 3 also extending diagonally across the plate, but at the opposite angle

from the first serrations, the two sets of serrations making the upper face of the plate similar to the cutting face of a double cut bastard file.

In operation, the plate is employed in conjunction with a check book, being placed below the check which it is designed to fill out. A piece of indelible carbon paper 4 is placed on the upper face of the plate which contains the serrations 2 and 3 in such a manner that its marking face will be against the back of the check, as shown in Fig. 2. The check 5 is then filled out preferably with an indelible pencil 6, the teeth left by the formation of the serrations 2 and 3 serving to puncture the check throughout the outline through which the pencil is moved, thereby leaving an irremovable inscription of the original filled out operation. The carbon paper 4 also serves to imprint on the back of the check the duplicate of the words and figures inscribed on the face by the indelible pencil 6, and this imprint on the back may at any time be easily read by holding the check before a looking glass in which the reversed reproduction of the inscription on the face may be easily read.

Having thus fully described this invention, what is claimed as new and desired to be secured by Letters-Patent, is:—

A check protector comprising a work plate having one face formed with a plurality of serrations across each other at angles, and a marginal flange surrounding the plate and standing at right angles to the plane of the face of the plate, and an indelible carbon sheet resting upon the serrated face of the plate between the flanges thereof, whereby when a check is placed on the carbon and an inscription made thereon by a marking implement the teeth formed by the serrations will puncture the check and the carbon to reproduce on the back of the check a duplication of the characters inscribed on the face.

In testimony whereof I affix my signature.

LUKE W. PARKER.
